UNITED STATES PATENT OFFICE.

JOHN L. DOW, OF MELROSE HIGHLANDS, MASSACHUSETTS, ASSIGNOR TO UNITED SHOE MACHINERY COMPANY, OF PATERSON, NEW JERSEY, A CORPORATION OF NEW JERSEY.

WELT-SEWING MACHINE.

1,094,838.

Specification of Letters Patent. Patented Apr. 28, 1914.

Application filed May 25, 1910. Serial No. 563,252.

To all whom it may concern:

Be it known that I, JOHN L. Dow, a citizen of the United States, residing at Melrose Highlands, in the county of Middlesex and State of Massachusetts, have invented certain new and useful Improvements in Welt-Sewing Machines; and I do hereby declare the following to be a full, clear, and exact description of the invention, such as will enable others skilled in the art to which it appertains to make and use the same.

The invention relates to welt sewing machines, and more particularly to means for holding the end of the welt while it is being attached to the upper and insole at the beginning of the sewing operation.

The object of the invention is to provide novel and improved welt holding means by which the welt may be held during the formation of any desired number of stitches at the beginning of the sewing operation. To this end one feature of the invention contemplates the provision in a welt sewing machine of a welt holding device which engages and holds the end of the welt at the beginning of the sewing operation, and which may be thrown out of operation at the will of the operator. With this construction the welt holding device continues to operate upon and hold the welt until it is thrown out of operation or rendered inactive by the operator, so that the welt may be securely united with the upper and insole before the welt holder ceases to act. Any suitable form of welt holding means and actuating mechanism, which will enable the welt holding device to be thrown out of operation at the will of the operator, may be employed. In order that the welt holder may continue to act upon the welt without putting additional strain or work upon the feeding devices which engage the shoe, it is preferred to so operate the welt holding device that it intermittently engages the welt and is moved with the welt during the feed of the shoe. With this construction the welt holding device assists in feeding the shoe, and may also act as a presser foot for holding the welt against the shoe during the loop drawing stroke of the needle, thus adding to the tightness of the seam.

In addition to the features above outlined, the invention includes certain further features and combinations of parts which will

be hereinafter explained and referred to in the claims, the advantages of which will be apparent to those skilled in the art.

In the drawings the invention is illustrated as embodied in the well-known Goodyear welt and turn sewing machine, but it will be understood that it is not confined in its application to this machine, but may be embodied in attachments for other forms of welt sewing machines, or may be otherwise incorporated in machines in which it is to be embodied.

The various features of the invention will be understood from an inspection of the accompanying drawings, and the following detailed description of the construction shown therein.

In the drawings Figure 1 is a left-hand side elevation of a Goodyear welt and turn sewing machine provided with an attachment embodying the features of the present invention in their preferred forms: Fig. 2 is a sectional plan view showing the construction of the welt holding attachment; Fig. 3 is a plan view showing the cam slide for throwing the welt holder into operation; Fig. 4 is a sectional view on line 4—4, Fig. 3; Fig. 5 is a detail plan view showing the welt holding finger and the front end of the carrier on which it is mounted; Fig. 6 is a side elevation of the parts shown in Fig. 5; Fig. 7 is a plan of the welt holding mechanism, showing the parts with the welt holding finger in engagement with the end of the welt; Fig. 8 is a similar view showing the position of the parts after the feed of the shoe has taken place; Fig. 9 is a sectional view on line 9—9, Fig. 2; and Fig. 10 is a sectional view on line 10—10, Fig. 2.

In the drawings, 1 indicates the back-gage or work-support, 2 the welt guide, 3 the needle, 4 the looper, 5 the feed point, and 6 the thread arm, these parts being constructed and arranged in the same manner, and operated by the same mechanisms, as the corresponding parts of the Goodyear welt and turn machine which is disclosed in the patent to French and Meyer, No. 412,701, October 8, 1889.

The means for engaging the end of the welt which projects through the welt guide, and holding it against the shoe at the beginning of the sewing operation, comprises a welt holding finger 7 secured at the front end of a slide 8 which is in turn mounted

upon an oscillating carrier arm 9. The welt holder slide 8 is mounted to move toward and from the work upon the end of the carrier arm 9, and is held upon the end of the 5 arm by screws 10 passing through slots 11 in the slide. The slide is forced in a direction to engage the welt holding finger with the welt by a spring 12, one end of which is connected with a pin 13 on the slide, and 10 the other end of which is connected with a block 14 secured to the carrier arm. The welt holder slide is held normally in retracted position against the tension of the spring 12 by means of a block 15 which is 15 secured to a slide 16, and engages a pin 17 projecting laterally from the slide 8. The slide 16 is mounted upon a supporting bracket 18, and is retained and guided thereon by a screw 19 engaging a slot 20 in the 20 slide. The slide 16 is held in retracted position by a comparatively heavy spring 21.

The carrier arm 9 is pivoted at 22 upon an arm 23 of the bracket 18, so that the arm may swing in the direction of the feed of 25 the work. The arm is held normally in its rearward or retracted position by a spring 24.

In order that the welt holding finger 7 may be moved positively in the direction of 30 the feed when the shoe is fed, a roll 25 is mounted in the block 14 on the carrier 9, and is arranged to be brought into the path of a cam rib 26 secured on the face of the cam disk 27. The cam roll 25 is mounted 35 upon the upper end of a stud 28 which is mounted to slide in the block 14, and is normally held in its lower position by a spring 29. The lower end of the stud 28 is arranged in the path of a lifting cam 30 secured 40 on the slide 16. When the stud 28 is in its normal position, the cam roll 25 is below the path of the cam rib 26, as indicated in dotted lines in Fig. 1. When the slide 16 is drawn forward, the cam 30 raises 45 the roll 25 into position to be operated upon by the cam 26.

The slide 16 is actuated through a bell crank lever 31, one arm of which engages a hole in the front end of the slide 16, and 50 the other arm of which is connected by a link 32 with a spring plate or treadle 33. In order that the welt holding mechanism may be thrown into operation in starting the machine, the treadle 33 is preferably 55 arranged directly above the starting treadle 34, and is so shaped that it partially overlaps the treadle. With this construction the operator may shift his foot off of the treadle 33 without releasing the starting treadle 34. 60 In Fig. 1 the parts are shown in position ready for the insertion of a shoe. When the parts are in this position the welt guide is retracted, and the cam 26 overlies the cam roll 25. When a shoe has been inserted, and 65 the operator starts the machine, he puts his

foot on the treadle 33 and springs this treadle downward with the starting treadle 34. At this time the slide 16 cannot move forward, since the cam roll engages the under side of the cam rib 26 and prevents the upward movement of the roll and stud 28. As the cam shaft 35 rotates, the welt guide immediately moves forward to bring the welt against the shoe, and then the cam rib 26 passes from above the cam roll 25. The 70 slide 16 then moves forward, lifting the cam roll 25 into the path of the cam 26, and also moving the block 15 away from the pin 17 so that the welt holding finger is engaged with the end of the welt, as shown in Fig. 7. 75 The cam rib and roll thus act to time the engagement of the welt holder with the welt. The welt holding finger now acts to hold the end of the welt against the shoe during the advance stroke of the needle, and during its return loop drawing stroke. After 80 the needle has drawn the loop through the work, the feed of the shoe takes place. As the feed point advances to feed the shoe, the cam 26 acts on the roll 25, moving the carrier arm 9 in the direction of the feed, so that the welt engaging finger 7 is positively 85 moved with the shoe during the feed, and assists in the feed of the work. After the feed has taken place, the cam 26 passes beyond the roll 25, so that the cam no longer interferes with the return movement of the carrier arm 9. The arm is held at this time against the tension of the spring 24 by the engagement of the welt holding finger 7 with 90 the work. Before the next feeding movement of the work takes place, the welt holding finger is disengaged from the work, so that the carrier arm 9 may return to normal 95 position, and then the welt holding finger is 100 reengaged with the work, preparatory to the next feeding movement, and firmly holds the welt against the shoe during the loop drawing stroke of the needle, and during 105 the next feeding movement of the shoe.

The means shown for disengaging the welt holding finger from the work comprises an arm 36 which is pivotally supported upon the rear end of a plate 37 secured to the link 38 through which the thread arm 6 is operated. The arm 36 is held in normal position by a spring 39. When the thread arm is in normal position, the arm 36 is in its rearward position, as indicated in the drawings. When the welt holder slide 8 moves forward to engage the welt holding finger with the welt, a pin 40 on the slide passes to the rear side of the arm 36, as indicated in Fig. 7. When the welt holder moves forward with the shoe during the feed, the pin 40 acts to deflect the arm 36 against the tension of the spring 39, as indicated in Fig. 8. After the needle has advanced through the work, the thread arm is operated to engage the thread, and the arm 36 is moved forward 120

so that its rear end passes to the front of the pin 40. The spring 39 immediately returns the arm to normal position, so that its rear end lies in front of the pin 40. Now 5 when the thread arms is returned to its normal position in giving up slack thread to the needle while the needle is drawing a loop of thread through the work, the arm 36 forces the welt holding slide back, thus disengaging 10 the welt holding finger from the welt. The spring 24 immediately swings the carrier 9 back into its initial position, as indicated in Fig. 7. This movement of the carrier takes the pin 40 off of the end of the 15 arm 36, so that the slide 8 is released, and the spring 12 acts to reengage the welt holding finger with the welt. This cycle of operations is repeated during each cycle of 20 operations of the stitch forming mechanism, so long as the slide 16 is held in its forward position by the operator, and the welt holder is given a 4-motion movement to intermittently engage the welt and move forward with it during the feed of the shoe. 25 After any desired number of stitches have been formed the welt holder may be rendered inactive or thrown out of operation by releasing the treadle 33. When this is done the slide 16 returns to normal 30 position, thus retracting the welt holding finger 7, and also allowing the cam roll 25 to move down out of the path of the cam 26.

While it is preferred to employ the construction and arrangement of parts shown 35 and described, it will be understood that this construction and arrangement is not essential, and may be varied and modified without departing from the broader scope of the invention.

40 Having explained the nature and object of the invention, and specifically described one construction in which it may be embodied, what I claim is:—

1. A welt sewing machine, having, in combination, stitch forming mechanism, a welt holder, and means for engaging the welt holder with the end of the welt, mechanism for actuating the welt holder independently of its engagement with the shoe, and means 45 for throwing the welt holder out of operation at the will of the operator, without stopping the machine, substantially as described.

2. A welt sewing machine, having, in combination, stitch forming mechanism, a welt holder arranged to hold the end of the welt in the rear of the sewing point, and mechanism for intermittently engaging the holder with and disengaging it from the welt during 50 the sewing operation, substantially as described.

3. A welt sewing machine, having, in combination, stitch forming mechanism, a welt holder arranged to hold the welt in the rear 55 of the sewing point, and mechanism for im-

parting a 4-motion movement to the welt holder to intermittently engage it with the welt and move it with the shoe during the feed, substantially as described.

4. A welt sewing machine, having, in combination, stitch forming mechanism, a welt holder arranged to hold the welt and move with the shoe during the feed, and mechanism for intermittently engaging the holder with and disengaging it from the welt during 7 the sewing operation and means for rendering the welt holder inactive after the end of the welt has been attached to the shoe, substantially as described.

5. A welt sewing machine, having, in combination, stitch forming mechanism, a welt holder, mechanism for throwing the welt holder into operation in throwing the driving mechanism of the machine into operation and means for throwing the welt holder out of operation at the will of the operator, without stopping the machine, substantially as described.

6. A welt sewing machine, having, in combination, stitch forming mechanism, a welt holder for holding the welt, means under the control of the operator for throwing the welt holder into operation, and mechanism for automatically timing the engagement of the welt holder with the welt with relation to the cycle of operations of the stitch forming mechanism, substantially as described.

7. A welt sewing machine, having, in combination, stitch forming mechanism, a welt holder for holding the welt, mechanism for throwing the welt holder into operation in starting the machine, and mechanism for automatically timing the engagement of the welt holder with the welt with relation to the cycle of operations of the stitch forming mechanism, substantially as described.

8. A welt sewing machine, having, in combination, stitch forming mechanism, a welt guide on one side of the needle, a welt holder for holding the welt on the opposite side of the needle, and mechanism for imparting feed and return movements to the welt holder and for intermittently engaging it with the work, substantially as described.

9. A welt sewing machine, having, in combination, stitch forming mechanism, a welt holder arranged to hold the end of the welt in the rear of the sewing point and to move with the shoe during the feed, and mechanism acting automatically to disengage the holder from the welt, return it to initial position, and reengage it with the welt, substantially as described.

10. A welt sewing machine, having, in combination, stitch forming mechanism, a welt holder for holding the welt in the rear of the sewing point, mechanism for actuating the welt holder during the sewing independently of its engagement with the shoe, means for throwing the welt holder into

operation, and means under the control of the operator for retaining the welt holder in operation, substantially as described.

11. A welt sewing machine, having, in combination, a welt holder, a carrier for the welt holder movable in the direction of the feed of the shoe, a cam for actuating the carrier in the direction of the feed, and a cam roll on the carrier movable into and out of the path of the cam, substantially as described.

12. A welt sewing machine, having, in combination, a welt holder carrier movable in the direction of the feed of the shoe, a 15 welt holder mounted on the carrier to move toward and from the shoe, a cam for actuating the carrier in the direction of the feed, and a cam roll on the carrier movable into

and out of the path of the cam, substantially as described.

13. A welt sewing machine, having, in combination, a welt holder carrier mounted for movement in the direction of the feed, a welt holder mounted on the carrier to move toward and from the shoe, a spring for advancing the welt holder, a controller slide for holding the welt holder normally retracted, a cam for actuating the holder in the direction of the feed, a cam roll on the carrier, and a cam on the controller slide 25 for moving the cam roll into the path of the cam, substantially as described.
